UNITED STATES PATENT OFFICE.

JOHN RICHARDSON, OF WEST BERKELEY, CALIFORNIA, ASSIGNOR OF ONE-HALF TO
MARY B. RICHARDSON, OF BERKELEY, CALIFORNIA.

WATER HEATER.

1,403,109.

Specification of Letters Patent. Patented Jan. 10, 1922.

Application filed March 16, 1921. Serial No. 452,724.

To all whom it may concern:

Be it known that I, JOHN RICHARDSON, a citizen of the United States, and resident of West Berkeley, county of Alameda, and 5 State of California, have invented a new and useful Water Heater, of which the following is a specification.

The present invention relates to improvements in water heaters and is designed particularly for use in connection with the laundry industry. Its particular object is to utilize the heat contained in waste smoke for the heating of water and to provide a tank for that purpose which in combination 10 with a particularly constructed furnace is especially adapted to present a large heat absorbing surface to said smoke and thus to absorb most of the heat contained in the same. A further object is to provide the 15 means of supplying additional heat to the water in the tank in case the heat furnished by the waste smoke is not sufficient to bring the water up to the desired temperature.

I attain these objects by means of the 20 mechanism illustrated in the accompanying drawing, in which Figure 1 represents a longitudinal vertical section through my device, Figure 2 an end view of the same, Figure 3 a transverse vertical section through 25 the same and Figure 4 plan view.

Referring to the drawing more particularly it will be seen that the water tank 1, which is here shown as being of rectangular shape rests on the furnace 2. The latter 30 may be of any form and is indicated in the drawing as consisting of a substantially rectangular housing 5, made preferably of brick and covered by a metal plate (3), from which the smoke-stack (4) extends and 35 which is provided with an opening (10), somewhat smaller than, but in its shape conforming to the bottom of the tank, so that the latter may rest on the edges defining said opening. The furnace is equipped with any 40 kind of heating means, as for instance the oil burner (6) shown in the drawing entering the furnace through the opening (7).

The tank is provided with a number of 45 downwardly extending tubes (8) which are closed at the lower ends (9) and open at the tops (11). They are rigidly fastened to the bottom of the tank and extend a small distance above the top surface of the bottom to facilitate the cleaning of the tubes 50 and of the bottom of the tank. In order to

clean said tubes, a person would preferably insert a pipe or a hose connected with a water supply into the same, turn on the water and flush out any rust or dirt that may have accumulated in said tubes. If the tops of 55 the tubes were flush with the top surface of the bottom of the tank, the rust or dirt flushed out by the water might flow right back into the same, whereas in the arrangement proposed in the present case the slight 60 elevation of the tops of the tubes above the surface of the bottom will prevent such flowing back.

At one end of the furnace I provide an 65 opening (12) connecting with the flue (14). The opening is so situated with reference to the smoke-stack (4), that smoke entering the furnace through the flue (14) will pass 70 between and around the tubes 8 into the smoke-stack.

As I mentioned before, my device is 75 designed in connection with laundries mainly in which one or more furnaces are needed to furnish live steam for various purposes and in which, under the present system, the 80 smoke from the said furnaces after having performed its work, still has a temperature of some 500° Fahrenheit, which normally goes to waste, and it is the object of my invention to lead said smoke through the flue 85 (14) into my furnace, so that it may be further utilized to heat the water to be used for washing, which does not require a temperature equal to the boiling point of the water. It will be easily understood that the tubes 90 present an excellent means for absorbing heat from the smoke passing them. The water contained in said tubes will heat almost instantaneously and cause a violent circulation in the water, the hot water rising and 95 the colder water gravitating into the tubes to be there heated and rise again.

While thus designed for special purposes, I do not wish, however, to confine my invention in any way, but desire to be protected 100 on any heating tank embodying my specific features.

I claim:

In a water heater and in combination with a furnace having an open horizontal top, a 105 water tank adapted to normally close said horizontal opening in the top of the furnace and having in its bottom a plurality of staggeredly arranged tubes extending from the bottom of the tank through said horizontal 110

opening in the top of the furnace and presented vertically within the fire box of the furnace, said tubes being closed at their lower ends and open at their upper ends, 5 and with the open upper ends extending slightly above the bottom of the said tank, and said furnace also having a smoke stack and a flue connection in the fire box on opposite sides of the staggeredly arranged

tubes, said smoke stack and said flue connection establishing an exhaust and intake respectively for the furnace; whereby smoke may be introduced into the furnace from an exterior source of supply and passed around the staggeredly arranged tubes before being 15 exhausted through the smoke stack substantially as and for the purpose described.

JOHN RICHARDSON.
